UNITED STATES PATENT OFFICE.

VICTOR MORDEN, OF VICTOR, CALIFORNIA, ASSIGNOR OF ONE-SIXTH TO THEODORE HEIL AND ONE-SIXTH TO PETER HEIL, BOTH OF VICTOR, CALIFORNIA.

COMBINED CIGARETTE AND MATCH COMPACT.

Application filed February 9, 1925. Serial No. 7,820.

This invention relates to improvements in smokers' articles, and particularly to one of especial benefit and appeal to smokers of ready made cigarettes.

5 The principal object of my invention is to provide a combined cigarette and match compact in which, as the term implies, a certain number of cigarettes, as well as matches therefor, are arranged as a single unitary article.

10 My improved compact has the outward appearance and is preferably the same size as the ordinary package of cigarettes and will have but very few less than the usual 15 number of cigarettes if put up in such size.

The match container is so arranged that while any match is readily accessible when the package is opened to remove the cigarettes in the usual manner, the matches and 20 cigarettes are maintained in definitely associated or unitary relation as long as the package is not destroyed.

25 This novelty compact should appeal to all cigarette smokers since, as will be evident, the need of purchasing separate cigarette and match packets is obviated, as well as the frequent inconvenience of carrying and using two such separate and individual packets. This is especially true with Army 30 and Navy men whose pockets are usually few and of small size.

35 Further, the compact is a great convenience and a time saver in use and the annoyance and inconvenience incident to the misplacing of a match box or the initial failure to buy one when purchasing cigarettes, is avoided.

40 The package may be made up without deviating from present methods and the cost of sale to the public need not be more than that of an ordinary package though worth much more from the standpoint of convenience etc. as above set forth.

45 A further object of the invention is to produce a simple and inexpensive device and yet one which will be exceedingly effective for the purpose for which it is designed.

50 These objects I accomplish by means of such structure and relative arrangement of parts, as fully appear by a perusal of the following specification and claim.

55 In the drawings similar characters of reference indicate corresponding parts in the several views.

Fig. 1 is a perspective view of the com-

pact showing the same as opened for use.

Fig. 2 is a longitudinal section of the compact before being opened.

Referring now more particularly to the characters of reference marked on the drawings, the package proper, which forms the enclosure for both cigarettes and matches, is made as usual from a sheet of paper, lead or tin foil or the like folded lengthwise to form a relatively narrow rectangular container and then folded and sealed at top and bottom as at 2 to make the container of the height of the cigarettes 3 therein.

An outer wrapper of paper 4 to serve as a label giving the brand of cigarettes etc. is placed about the sides of the wrapping element and terminates a short distance from the top of the latter.

Fitting between the sides of the container 1 at one end thereof is an open ended narrow casing or sleeve 5 of cardboard or the like, the face of which adjacent the end of the container 1 is preferably glued to the material of the latter.

Slidable in the casing is a match box 6 to contain a suitable number of matches 7, said box being opened along the side facing the adjacent end of the container 1 as shown in Fig. 1. The box 6 is the same length as the casing 5 or container 1 and to enable said box to be drawn out when desired to get at the matches, the outer face of said casing at both ends has centrally located finger notches 8 cut down about to the level of the outer wrapper 4.

On the end of the wrapper adjacent the match container is a strip of sand paper 9 or the like, while directions with regard to where to open the package are preferably printed on said wrapper at the match box 95 end thereof as at 10.

In operation the user as is customary tears open the container 1 at the end having the above named directions thereon for a small portion of its extent the tear of itself usually 100 extending to the adjacent edge of the outer wrapper 4, which forms a protection against further tearing of the main container of package material.

This operation exposes the adjacent notch 105 8 in the match box casing so that when a cigarette is withdrawn from the package the adjacent end of the match box may be engaged by a fingernail and the box moved out to allow the match to be withdrawn, as 110

shown in Fig. 1. This done, the box is I claim as new and useful and desire to 25 pressed back into its casing, preventing any secure by Letters Patent is:

The casing 5 is preferably made open at 5 both ends so that should the package be opened at the other end by mistake the matches are available without opening the opposite end. The depth of the match box is such that it takes the place of a single 10 transverse row of cigarettes, while such a depth gives ample room for a number of matches more than equal to the number of cigarettes in the package.

From the foregoing description it will 15 be readily seen that I have produced such a device as substantially fulfills the objects of the invention as set forth, herein.

While this specification sets forth in detail 20 the present and preferred construction of the device, still in practice such deviations from such detail may be resorted to as do not form a departure from the spirit of the invention, as defined by the appended claim.

Having thus described my invention, what

A combination cigarette and match compact comprising a container for the cigarettes and a container for the matches, the two containers being disposed side by side and 30 enclosed in a common relatively light wrapping member, the match container including a sliding drawer in a relatively inflexible cover, the cover at one end being provided with a notch to allow the sliding drawer 35 to be engaged by the fingers to withdraw it from the cover, and a second and relatively heavy wrapping element enclosing the compact and terminating a short distance below the top of the match container whereby 40 the first wrapper may be torn down to the top edge of the second wrapper to expose the notch and drawer so that the latter may be grasped and withdrawn from its cover, and at the same time keep the two 45 containers securely wrapped together.

In testimony whereof I affix my signature.

VICTOR MORDEN.
